KNIFE SHARPENING MACHINE

Erwin Roeder, Ebenezer, N. Y.

Application July 5, 1947, Serial No. 759,085

13 Claims. (Cl. 51—115)

1

This invention relates to a knife-sharpening machine, and more particularly to that type of machine in which knife blades are removably held and sharpened at opposite sides thereof.

One of the objects of my invention is to provide a knife or blade sharpener which is adapted to be power driven and is so constructed that a plurality of axially aligned sharpening disks are included, against opposing sides of which knives or knife blades are arranged to contact under desired pressures and in which improved means are provided to automatically withdraw the knives or blades from one disk and direct it against the surface of another so that both sides of the blades will be alternately acted upon and the blade sharpened to like degrees at opposite sides thereof.

A further object of my invention is to provide new and novel means for oscillating the knives or knife blades between sharpening and grinding elements so that opposite sides of the knife or blade are alternately acted upon with the bevel of both sides of the knife or blade finished at like angles.

A still further object of my invention is to provide means whereby the pressure of the knives or knife blades against the sharpening or grinding elements can be varied and whereby novel and positive means for oscillating the knives or knife blades are provided to assure action against the knives or knife blades to equal degrees at opposite sides thereof.

A still further object of my invention is to provide simple and effective means whereby the bevel of the knife blade at its cutting edge can be easily varied to meet the requirements for which the particular knives or knife blades being sharpened are to be used.

With the above and other objects in view to appear hereinafter, my invention consists of the novel features of construction and in the arrangement and combination of parts to be hereinafter described and more particularly pointed out in the subjoined claims.

In the drawing Fig. 1 is a side elevation of my improved knife sharpening or grinding machine. 45

Fig. 2 is a top plan view of the same.

Fig. 3 is a rear elevation of the machine.

Fig. 4 is a front elevation of the same.

Fig. 5 is a transverse section taken on line 5—5, Fig. 2, looking in the direction of the arrow crossing said line.

Fig. 6 is a longitudinal section taken on line 6—6, Fig. 1 looking in the direction of the arrow crossing said line.

Fig. 7 is a longitudinal section, on an enlarged 55

2

scale, of a portion of one of the blade-tensioning means forming part of the blade oscillating or reversing mechanism.

Fig. 8 is an enlarged section taken on line 8—8, 5 Fig. 7.

Fig. 9 is a detailed view of the blade-carrying rock-shaft, its bearing, the standard or upright on which said bearing is formed, and a portion of the frame on which the operating mechanism of my improved machine is mounted.

Fig. 10 is an enlarged longitudinal section through the upper end of one of the knife or blade-carrying rock-shafts, showing the anti-friction thrust bearing associated with the standard 15 in which said rock-shaft is secured.

Fig. 11 is an enlarged transverse section taken on line 11—11, Fig. 5.

Fig. 12 is an enlarged vertical section through a portion of a rock-shaft standard or upright.

Fig. 13 is a detailed sectional view showing the manner of connecting the trip levers to the lower ends of the rock-shaft standards or uprights.

Fig. 14 is a detailed sectional view showing the manner of adjustably mounting the lower ends 25 of the standards or uprights in which the knife or blade-carrying rock-shafts are journaled.

Fig. 15 is a longitudinal section of the blade-holder showing the same adjustably mounted on one of the knife or blade-carrying rock-shafts.

Fig. 16 is a transverse section through one of the sprocket chains and the trip-roller carried thereby.

Reference being had to the drawings in detail, like numerals of reference refer to like parts throughout the several figures of the drawings.

The reference numeral 20 designates the frame or support of the machine which includes legs 21, connecting a base 22 with a table 23. Formed integral with said frame or support is a hollow depending portion serving as a reservoir 24 which is open at the top and has the upper ends of its side and end walls connected to the table 23.

The frame or support, including the reservoir 24, may, as stated, be cast or otherwise fashioned in one integral piece, or if desired the reservoir may be formed separately and attached to the table portion of the frame or support.

The said table portion may be said to have an opening therein which forms the open top of the reservoir and at opposite sides of the opening the frame or support is provided with suitable bearings 25, in which a drive shaft 26 is journaled, one end of the shaft extending any desired distance beyond the adjacent bearing for attachment thereto of any suitable medium whereby rotary

motion may be imparted to the shaft from an electric motor or any other source of power.

On this shaft 26 sharpening or grinding disks 27 are secured in any approved manner so that they will travel with the shaft when the latter is rotated by a suitable source of power.

In the drawings I have shown three sharpening or grinding disks, but any other number of disks may be used if desired. When using three disks, which I believe most advantageous, they are spaced apart and so maintained by spacing sleeves 28 which encircle said drive shaft and have their ends in contact with the sharpening or grinding disks 27, the disks being clamped firmly against the ends of said spacing sleeves by clamping nuts 29 threaded onto the shaft 26 and bearing against the outer faces of the outermost disks. For this purpose the shaft 26 has its intermediate portion 30 enlarged and the ends of said intermediate portion screw-threaded, as at 31, which threaded ends extend outwardly beyond the outer faces of the outermost disks and have the clamping nuts 29 threaded thereon. It will be apparent therefore that upon tightening the clamping nuts, the disks will be tightened against the ends of the spacing sleeves, as clearly shown in Fig. 6.

The lower portions of said sharpening or grinding disks 27 extended downwardly into the reservoir 24, which is supplied with a liquid substance 32 in the form of a sharpening solution having abrading qualities, and which solution is taken up by the disks as the latter are rotated with their lower portions moving through the reservoir. Thus a continuously fresh layer or coating of the sharpening solution is supplied to the opposite sides of the sharpening or grinding disks and with the view of agitating the solution within said reservoir so as to prevent settling of the abrading material and to hold the latter in suspension within the liquid, agitating means 33 are applied to the outer sides of the outermost disks, which sides are inactive as grinding surfaces, regardless of the number of disks used.

Each of these agitating means comprises a bar 34 disposed radially along the outer side of each of the outer disks, which bar has its inner end threaded into the clamping nut 29. The outer end of each of said bars is provided with an outstanding paddle 35 so that one of the wide surfaces of each paddle carries the sharpening solution forwardly and upwardly during the rotation of the sharpening or grinding disks and thus keeps the liquid agitated at all times.

Mounted on the table 23 of the frame or support in rear of the sharpening or grinding disks are standards or uprights 36 and these are transversely adjustable on the frame or support for a purpose to appear hereinafter. As clearly shown in the drawings these standards comprise flat upright members 37 provided at their lower ends with laterally-extending flanges 38 and at their upper ends with obliquely-disposed elongated shaft bearings 39 inclined forwardly and downwardly from the upper ends of said standards and they are adapted to be disposed in planes centrally between the sharpening or grinding disks 27.

The standards have bolts 40 threaded thereinto which extend upwardly through transversely-disposed slots 41 formed in the table 23 of the frame or support. It will be apparent therefore that upon loosening the bolts 40, the standards 36 may be moved toward or from each other depending on the requirements for best sharpen-

ing conditions, invariably positions in which the standards are absolutely centered with respect to planes passing exactly centrally between the sharpening or grinding disks.

5 Mounted in the shaft bearings 39 of the standards 36 are rock shafts 43, which I also refer to as knife or knife blade carriers. One of said shafts extends into the space between the center sharpening or grinding disk 27 and the disk to the left thereof, as viewed in Fig. 4, while the other extends centrally into the space between said center sharpening or grinding disk and the disk to the right thereof, and since each shaft bearing 39 is centered on a standard 36, the rock-shafts will have their axes coincident with a plane passing exactly midway between two spaced-apart disks.

It is to be noted that on each rock-shaft there is a knife or blade-holder 44 in which a knife or knife blade 45 to be sharpened is placed. The blade-holder 44 is disposed parallel with the shaft and comprises a longitudinal flat member 46 having ears 47 at opposite ends, said ears being spaced apart a greater distance than the length 25 of the knife or knife blade to be sharpened, and projecting medially downwardly and rearwardly from the flat member 46 is a screw-stud 48, which is threaded into or through a threaded opening 49 in the rock-shaft 43. The blunt edge of the 30 knife or knife blade 45 is placed against the outer face of the flat member 46 and when so positioned set screws 50 passing through the ears 47 and impinging against the ends of the knife or blade clamp the latter securely in the knife or blade holder with the edge of the knife or blade 35 to be sharpened along the extreme outer region.

As clearly shown in Figs. 5 and 10, a thrust bearing 51 is secured to each rock shaft near its upper or outer end and if desired this bearing 40 may be an anti-friction bearing, such as shown in Fig. 10, and be so arranged that the anti-friction balls 52 thereof travel in contact with the upper end of the obliquely-disposed shaft bearing. The thrust bearing may, however, be common collars, such as shown in other figures of the drawings. It is to be noted that the obliquely-disposed shaft bearing 39 is cut away along its upper or outer portion and therefore the wall of this bearing is not continuous, and as so constructed has a slot 53 formed along said bearing wide enough at its narrowest portion to permit the rock shaft to be drawn upwardly out of its bearing, while allowing the blade holder and the knife or knife blade thereon to be retained in place on the rock-shaft while so moved. Passing transversely through and journaled in the spaced-apart standards 36 is a shaft 54 and the ends of this shaft extend outwardly a distance beyond the outer surfaces of said standards as clearly 55 shown in Figs. 3 and 4.

On the outer ends of this shaft sprocket wheels 55 are keyed or otherwise secured, or if desired these sprocket wheels may be rotatable on the shaft while the shaft is held stationary in the standards. Passing around the sprocket wheels 65 55 and sprocket wheels 56 keyed or otherwise secured to the shaft 26 are sprocket chains 57. As clearly shown in Fig. 6, the sprocket chains 51 are arranged adjacent to the bearings 25, and so disposed that they are in the same plane as the sprocket wheels 55. As hereinbefore stated, shaft 26 on which the sprocket wheels 56 are mounted is rotated by any suitable source of power and through the medium of the sprocket chains 57 these sprocket wheels 56 cause rotation

of the sprocket wheels 55, which are utilized in conjunction with the sprocket chains 57 to actuate the means for oscillating the knives or knife blades, which may also be referred to as trip and pressure mechanism, to be presently described.

The trip and pressure mechanism referred to comprises several parts connected to the rock shafts 43 and actuated by the sprocket chains 57, and for such purposes a bar 58 extends outwardly from each rock-shaft, the bars being entered in said rock-shafts and fastened in any approved manner. Each of these bars extend in an outward direction from the rock-shaft to which it is secured and these bars are, therefore, directed in opposite directions. To the outer ends of these bars 58, the upper ends of links 59 are secured, said links having connection at their lower ends with trip levers 60, one of which is pivotally secured to the lower outer end of each of the standards 36, and for this purpose a rock sleeve 62 is rotatably mounted on a pivot bolt 63 passed through the base of each standard 36. The pivot bolts 63 may be reduced at their outer ends to receive nuts 64 which bear against shoulders formed by reducing the diameter of said bolts and thus provide free rotative movement of the sleeves into which the trip levers 60 are threaded.

I preferably connect the upper ends of the links 59 with the laterally extending bars 58 by means of screws 66 which pass loosely through slots 67 in the upper ends of said links and enter said bars, said slots being preferably of key formation with the enlargement of each key-formed slot at its lower end; the arrangement being such that there is a certain amount of play provided between the bars 58 and links 59. By having the enlargements of the slots of greater diameter than the diameter of the heads of the screws 66, the parts connected by the screws can be easily disconnected.

The connection between the trip levers and the links 59 is established by passing screws 65 loosely through said links and entering the screws into threaded openings in the outer ends of the trip levers.

Each of the sprocket chains 57 is provided with a trip roller 68; the pintle of which serves as a means of connection between two adjacent links of the sprocket chain and it is to be noted that the trip roller of each sprocket chain extends inwardly therefrom; also that the trip rollers of the sprocket chains are so positioned that the pintle of one is located on its sprocket chain exactly halfway around the chain from the pintle of the trip roller on the other sprocket chain, the purpose for which will appear hereinafter.

As clearly shown in Fig. 1, the trip roller 68 on the left hand sprocket chain has been brought into contact with the trip lever 60 at the same side of the machine due to the chains being at a lesser inclination than said trip lever when in normal position and it has reached a point where it will have caused maximum depression or swinging movement of said trip lever. Now, upon further movement of the sprocket chain, the trip roller will gradually ascend and will allow said trip lever to retrieve its normal position. This depressed position of the trip lever 60 will have caused the link 59 connected thereto to draw the bar 58 to which said link is connected downwardly, and thus the rock-shaft through which said bar is passed will be swung in one direction to the full extent intended for the same. Such

movement of the rock-shaft will have brought the knife or knife blade between the intermediate disk and the left hand disk, as viewed in Fig. 4, against the latter disk and also by reason of connecting means to be presently described, the knife or knife blade between the intermediate disk and the right hand disk, as viewed in Figs. 1 and 4, will have been swung against the intermediate disk.

Such cooperation between the knives or knife blades results from the following means, which comprise an angular or L-shaped rod 69 for each rock-shaft 43, having one arm 70 passed through the rock-shaft and its other arm 71 arranged parallel with said rock-shaft, or substantially so. The arm 70 is adjustable in the rock-shaft 43 and is held in adjusted position by means of a set screw 72 threaded axially into said rock-shaft and impinging against said arm.

The portions of the arms 70 extending downwardly through the rock-shafts 43 are connected together at their lower ends by a link 73, so that the rock-shafts are rocked in unison. Each rock-shaft is actuated by one of the trip levers 60 and the other simultaneously therewith through the connecting link or means 73 between the rock-shafts provided by the angular or L-shaped rods 69 and the link 73 connecting the latter; thus upon rocking either of said rock-shafts 43, one clockwise and the other counterclockwise, both are actuated in the same direction.

For this purpose each angular or L-shaped rod 69 has associated therewith a retractile spring 74, one end of which is secured to the arm 71 of said rod, while the other end is secured to a contractile device comprising two parts 75, 76, adjustably connected together, as at 77, so that the contractile device can be lengthened or shortened to diminish or increase the tension of spring 74. It will be apparent, therefore, that the parts 69, 74, 75 and 76 form tensioning mechanism and that a quick approximate pressure adjustment for the knives or knife blades can be made by merely adjusting the arms 70 of each L-shaped rod 69 in the rock-shaft through which it is passed, and fine and final exact pressure adjustments are made by lengthening or shortening the contractile device.

The connecting link or means 73 also serves as part of the trip and pressure mechanism, or blade-tensioning mechanism as it may also be termed, by means of which the knives or knife blades are held against their respective sharpening or grinding disks with the desired pressure; it being apparent that the tension of the springs 74 controls the pressure of the knives or knife blades against the sharpening or grinding disks.

The lower end of each contractile device is rotatably mounted on a stationary rod or anchor 78 which is threaded into a standard 37 and extends rearwardly therefrom and thence upwardly at an inclination substantially at a right angle to the contractile device, forming part of the blade tensioning mechanism. In order to adjust the two parts of the contractile device relatively, it is simply necessary to rotate one while holding the other against rotation. Thus the device will be shortened or lengthened, depending on the part rotated and the direction of rotation thereof. When a contractile device is lengthened, its spring 74 will become slightly relieved of strain and the pressure of the associated knife or knife blade against its co-operating sharpening disk will be slightly reduced. The shorten-

ing of the contractible device will result in a corresponding increase of pressure of the knife or knife blade against its co-operating sharpening disk.

So that the contractible device may be rotatable on the stationary rod or anchor 18, the latter is provided with an annular groove 19, into which a set-screw 80 is entered. The inner end of said set-screw being reduced in diameter and unthreaded so that a free terminal is provided for the same, which will allow free rotation of the contractible device on the rod or anchor 18.

The operation of the device is as follows:

Preparatory to sharpening knives or knife blades, a suitable liquid substance is placed within the reservoir 24 to a level which will assure complete moistening of the sharpening or grinding disks when rotated over the area engaged by the knives or knife blades, and the motor, not shown, for rotating the shaft 26 will, by reason of the sprocket wheels 55 being secured thereto, cause movement of the sprocket chains 57. These chains in turn pass around the sprocket wheels 56, thus providing an orbital path of travel for the sprocket chains. It will be clear from the preceding description that one sprocket chain is located at each side of the machine and that the sharpening or grinding disks 27 are located between these sprocket chains.

Each sprocket chain has its trip rollers 68 extending inwardly therefrom and, as stated, these are disposed relatively at directly opposite points of the sprocket chains so that each trip roller is idle during the major portion of the cycle of movement of the sprocket chain from which it extends while the other is brought into action during a minor portion of the cycles of movement of the sprocket chain from which it extends and always approximately midway of the idle movement of the first-mentioned trip roller. These trip rollers alternately engage the trip levers 60, and thus through the medium of the links 59 cause the rock-shafts, which also serve as blade or knife blade carriers or supports to rock in opposite directions.

Viewing the machine as shown in Fig. 4, the rock-shafts have been swung counter-clockwise, due to the fact that the trip roller extending from the sprocket chain at the left of the machine has engaged the trip lever 60 at the same side of the machine, and thus caused said lever to swing downwardly and its connected link to descend, with the result that the bar 58 connected to said link has been drawn downwardly and caused counter-clockwise movement of the left hand rock-shaft. During this action the angular or L-shaped rod 69 passed through said rock-shaft will have been swung from a position to the right of the center of said rock-shaft to the position shown therefor at the left of said center, and by reason of the lower ends of said angular or L-shaped rods being connected together by the link 13, the right hand rock-shaft shown in said figure will have been correspondingly moved.

The tensioning mechanism associated with each rock-shaft serves to hold the arm 11 of its associated angular or L-shaped rod 69 to either the left or right of a vertical plane passing axially through the rock-shaft, and during the movement of said rock-shaft through one-half of its clockwise or counter-clockwise movement, the retractile spring 14 connected to said arm will have become expanded and immediately on said arm passing said plane, or what may be termed the dead-center, said spring will immediately re-

cover itself and exert its force to move the arm 11 of said angular or L-shaped rod to the left.

Such movement of the rock-shafts will cause the knives or knife blades 45 carried thereon to swing against the right hand face of the left hand and intermediate sharpening or grinding disks, and due to the fact that the knives or knife blades are firmly clamped in the knife or blade holders and the latter are rigidly mounted on the rock-shafts, the sharp edges of the knives or knife blades will be held against the surfaces of the sharpening or grinding disks at the desired angle to assure the proper bevel and sharp edge being established along the outer or thin edge of the knife or knife blade.

It is to be noted that the knife blade holder is adjustably fastened within the rock-shaft and that by unthreading the screw stud 48 the blade carrier may be spaced a greater distance from the rock-shaft, with the result that the angularity of the bevel will be increased. It will be clear therefore that variations in the bevel of the knife or knife blade being sharpened may be had by adjusting the blade holder with respect to the rock-shaft on which it is mounted.

It is also to be noted that by reason of the rigid connection provided by the blade holder and the rock-shaft and the non-movable disposition of the knife or knife blade within its holder, the pressure of the blades against the disks can be varied by varying the tension of the retractile spring 14, which may be accomplished by increasing or decreasing the length of the contractible device provided by the two parts or connected members 75 and 76, as hereinbefore stated.

It is also to be noted that each knife or knife blade can be easily removed from the machine, or inserted thereinto, by merely disengaging the set-screw 80 from its annular groove 19, and by disconnecting the lower end of the link 59 from the trip lever 60, after which the rock shaft can be withdrawn lengthwise from its bearing 39, the width of the slot 53 of which is sufficient to allow the knife blade holder and its stud to be passed upwardly therethrough or to be inserted downwardly therethrough for positioning the knife or blade in operating relation to its sharpening or grinding disks.

It is also to be noted that during the rotation of the sharpening or grinding disks the liquid within the reservoir becomes agitated so as to keep the sharpening substance in suspension within the liquid and to assure an equal distribution thereof over the entire grinding or sharpening areas of the disks.

It is further to be understood that by reason of the trip rollers 68 alternately engaging the trip levers 60 at opposite sides of the machine, the rock-shafts are swung alternately clockwise and counter-clockwise so that the knives or knife blades, under clockwise movements of the rock-shafts, as shown in Fig. 4, will cause the knives to be swung against the left hand surfaces of the intermediate and right hand sharpening and grinding disks, and under the counter-clockwise movement said knives or knife blades will be swung against the right hand surfaces of the intermediate and left hand sharpening or grinding disks.

While I have made provisions for utilizing a liquid sharpening solution for moistening the grinding or sharpening disks, I particularly wish to stress the fact that in many instances the disks are used without a liquid solution being applied

thereto. However, when resorting to finer sharpening operations, which may be referred to as honing of the knives or knife blades, the sharpening disks, or honing disks as they may more particularly be referred to, depend on the use of a sharpening solution, and it is to be understood that such sharpening solution need not necessarily include an abrasive substance which it is necessary to maintain in suspension, since in some instances oil may be poured into the reservoir and serve to aid in sharpening or honing knives or knife blades. The sharpening or honing disks may vary in abrading qualities, depending on the nature of the knives or knife blades being sharpened.

Having thus described my invention, what I claim is:

1. A machine for sharpening knives or knife blades, comprising a suitable support, a shaft mounted on said support, three spaced-apart axially aligned sharpening disks secured to said shaft so as to rotate therewith, said disks being disposed to provide a center disk and two end disks, means for rotating said shaft, sprocket wheels on said shaft between which said sharpening disks are located, two shaft bearings mounted on said support, a rock-shaft journaled in each of said shaft bearings and extending forward between adjacent sharpening disks, a knife or blade holder carried by each rock-shaft, a shaft parallel with and in spaced relation to said first-mentioned shaft, sprocket wheels on said last-mentioned shaft in alinement with said first-mentioned sprocket wheels, a sprocket chain trained around alined sprocket wheels at each side of the machine, a trip device carried by each sprocket chain, combined trip and tensioning mechanism interposed between each trip device and each of said rock-shafts to cause rocking movement of said rock-shaft in a given direction, and means for connecting said rock-shafts together so as to cause rocking movement of both rock shafts in unison, depending on the direction of movement of the rock-shaft actuated by its cooperating trip and tension mechanism.

2. A machine for sharpening knives or knife blades, comprising a support, a shaft extending transversely above said support, three spaced-apart sharpening disks rotatable with said shaft, sprocket wheels on said shaft between which said sharpening disks are located, standards mounted on said support in rear of said sharpening disks, a second shaft rotatable in said standards, sprocket wheels secured to said second shaft in alinement with first-mentioned sprocket wheels, sprocket chains trained over each pair of alined sprocket wheels, a trip roller on each sprocket chain, said standards having shaft bearings at their upper ends inclined downwardly and forwardly, rock shafts rockable in said shaft bearings and extending downwardly and forwardly to positions between the intermediate and outer of said three sharpening disks, said rock-shafts extending upwardly a distance above said shaft bearings and having arms extending radially therefrom, links connected to the outer ends of said arms, trip levers connected to the lower ends of said links and against each of which the trip roller of one of said sprocket wheels is adapted to ride while traveling around said sprocket wheels, means of connection between said rock-shafts to cause them to rock in unison and move said rock-shafts in like directions so as to position the knives or knife blades carried thereby against said sharpening disks, each trip

roller and its cooperating trip lever causing movement of said rock shafts through one-half their movements in each direction, and tensioning means to cause movement of said rock-shafts through the remaining half in each direction.

3. A knife sharpening machine, comprising a support, a shaft mounted on said support and having spaced-apart bearings thereon, a plurality of axially-aligned sharpening disks arranged in spaced-apart relation on said shaft, rock-shafts journaled in suitable bearings carried by said support and arranged with one end extending centrally into each space between adjacent sharpening disks, a knife or knife blade carried by each rock-shaft and adapted to be forced under spring pressure alternately against the two opposing faces of spaced-apart disks into which said rock-shaft extends so that at least one of said disks has knives or knife blades associated therewith and disposed to contact opposite sides thereof, a sprocket wheel on said first-mentioned shaft at each side of the machine, sprocket wheels carried by said support in rear of and spaced from said first-mentioned sprocket wheels, a sprocket chain trained around the sprocket wheels at each side of the machine, and means interposed between said sprocket chains and said rock-shafts to cause the latter to be rocked alternately in opposite directions so as to bring opposite sides of the knives or blades carried thereby against opposing faces of adjacent sharpening disks, said means including pressure and tensioning mechanism to cause the knives or blades to be subjected to like pressures at opposite sides thereof.

4. A machine for sharpening knives or knife blades, comprising a support, three spaced-apart rotatable sharpening disks carried by said support, a rock shaft extending into each space between adjacent sharpening disks also carried by said support; knives or knife blades carried by said rock-shafts and adapted to alternately engage said sharpening disks, spaced-apart sprocket wheels carried by said support and rotatable with said sharpening disks, a second pair of sprocket wheels carried by said support and alined with said first-mentioned sprocket wheels, sprocket chains trained around alined sprocket wheels and each sprocket chain having a trip roller, the trip roller of one sprocket chain being disposed half-way in the cycle of movement of the trip roller of the other sprocket wheel, trip levers adapted to be engaged and depressed by said trip rollers alternately, means between each trip lever and one of said rock-shafts to cause rocking movement of the latter so as to swing the knife or knife blade carried thereby against opposing faces of adjacent sharpening disks, and means to cause each rock-shaft to be actuated in unison with the other.

5. A knife sharpening machine, comprising a support, having a reservoir at its front end furnished with a sharpening solution, a shaft mounted on said support across the top of said reservoir, three sharpening disks rotatable with said shaft and having their lower portions normally disposed within said sharpening solution, a pair of sprocket wheels on said shaft between which said sharpening disks are arranged, standards mounted on said support in rear of said sharpening disks, a shaft journaled in said standards, sprocket wheels on said last-mentioned shaft alined with said first-mentioned sprocket wheels, sprocket chains trained over alined sprocket wheels at each side of the machine, a

trip roller on each sprocket chain extending inwardly therefrom, each standard having an elongated downwardly and forwardly inclined shaft bearing, a rock-shaft journaled in each of said shaft bearings and extending forwardly therefrom between said sharpening disks, each rock-shaft having a knife or knife blade secured thereto, a thrust bearing secured to each rock-shaft and supported by the upper end of the elongated shaft bearing of the latter, each rock-shaft extending upwardly and rearwardly beyond said thrust bearing, a bar extending radially from the upper end of each rock-shaft, a link connected to the outer end of each of said bars, a trip lever pivotally connected to the lower end of each standard and having connection with the lower end of one of said links, each trip lever being actuated by one of said trip rollers to cause rocking movement of its associated rock-shaft, an L-shaped rod extending radially through each rock-shaft at its upper end and being adjustable thereon, an anchor rod extending upwardly from each upright, a spring having one end connected to said L-shaped rod, and a contractile device comprising two telescopic parts connected to the other end of said spring and having connection with said anchor bar, said springs causing the rock-shafts to complete their rocking movement after reaching the dead center under actuation of said trip levers and serving to hold the knife or knife blades with the desired pressure against said sharpening disks.

6. A knife sharpening machine, comprising a support, a plurality of axially-aligned sharpening disks rotatably arranged in spaced-apart relation on said support, rock-shafts journaled in suitable bearings in rear of said sharpening disks and arranged with one end extending centrally into the space between adjacent sharpening disks, a knife or knife blade carried by said rock-shaft and adapted to be alternately brought into contact at opposite sides thereof with opposing faces of said sharpening disks, means interposed between said first-mentioned shaft and said rock-shafts to cause the latter to rock in their bearing, a retractile spring associated with each of said rock-shafts, a bar extending adjustably from each rock-shaft and having said spring connected thereto whereby a rough adjustment of the tension of said spring can be made, and contractile devices each having one end secured to a fixed point of the machine and its other end secured to one of said springs for placing the latter under the exact tension desired and thus cause knives or knife blades carried by said rock-shafts to be brought alternately against opposing faces of said sharpening disks with the exact pressure desired.

7. A machine for sharpening knives or knife blades, comprising a suitable support, three spaced-apart co-axial sharpening disks rotatably mounted on said support, two knife or blade carriers mounted on said support and each disposed to extend between two opposing sides of adjacent sharpening disks so that one of said disks is common to both knife or blade carriers, each knife or blade carrier having a knife or blade removably applied thereto adapted to engage opposing faces of adjacent spaced-apart sharpening disks, means to rotate said sharpening disks, and means to cause said knives or blades to be swung under predetermined pressure alternately against opposing faces of adjacent sharpening disks, said last-mentioned means including a rod extending through each knife or blade carrier to

provide a radial arm extending from opposite sides of said carrier and a spring connected to one of said radial arms to tension said carrier so as to hold the knife or blade thereon in position to be sharpened, and means to connect the other radial arms of said two carriers together to cause them to operate in unison.

8. A machine for sharpening knives or knife blades, comprising a suitable support, three spaced-apart co-axial sharpening disks rotatably mounted on said support, two knife or blade carriers mounted on said support and each disposed to extend between two opposing sides of adjacent sharpening disks so that one of said disks is common to both knife or blade carriers, each of said knife or blade carriers having a knife or blade removably applied thereto and adapted to engage opposing faces of adjacent sharpening disks, means to rotate said sharpening disks, arms extending radially from said knife or blade carriers connected together to move said carriers in unison, means to cause each of said arms to move through an arc of a circle, and other arms extending radially from said knife or blade carriers and spring-tensioned to move said carriers so as to swing the knives or blades applied thereto alternately against opposite faces of adjacent sharpening disks.

9. A machine for sharpening knives or knife blades, comprising a suitable support, a shaft mounted on said support, three spaced-apart axially-aligned sharpening disks secured to said shaft so as to rotate therewith, said disks being disposed to provide a center disk and two end disks, means for rotating said shaft, two shaft bearings mounted on said support, a rock-shaft journaled in each of said shaft bearings and extending between adjacent sharpening disks, a knife or blade holder carried by each of said rock-shafts, a second shaft parallel with and in spaced relation to said first-mentioned shaft, means to rotate said second shaft from said first-mentioned shaft, trip mechanism controlled in action by said means, combination trip and tensioning mechanism actuated by said trip mechanism and interposed between said trip mechanism and each of said rock-shafts to cause rocking movement of said rock-shafts, and means for connecting said rock-shafts together so as to cause rocking movement of both rock-shafts in unison, depending on the direction of movement of the rock-shaft actuated by its cooperating trip and tension mechanism.

10. A machine for sharpening knife blades, comprising a suitable support, a shaft journaled transversely on said support, sharpening disks arranged on said shaft in spaced-apart relation, a standard mounted on said support in planes in rear of said sharpening disks and centrally there-between and having a downwardly and forwardly inclined shaft-bearing at its upper end provided with an upwardly opening slot extending its full length, a rock-shaft rockable in said shaft-bearing and extending forwardly between said sharpening disks, a knife-blade holder carried by said rock-shaft and having a knife blade secured thereto, said knife-blade holder being capable of alignment with the slot in said shaft-bearing to permit the insertion of said rock-shaft and its knife blade lengthwise into said shaft-bearing and its removal lengthwise therefrom, a thrust bearing secured to said rock-shaft and bearing against the rear upper end of said shaft-bearing, means to rotate said sharpening disks, means to rock said rock-shaft to swing the knife blade carried

by said knife-blade holder alternately against the sharpening disks at opposite sides of said rock-shaft, pressure and tensioning means connected to said rock-shaft, means for actuating said pressure and tensioning means to govern the pressure with which said knife blade is swung against said sharpening disks.

11. A machine for sharpening knives or knife blades, comprising a suitable support, a shaft transversely mounted on said support, two axially-aligned spaced-apart sharpening disks secured to said shaft, means to rotate such shaft, a standard mounted on said support in planes in rear of said sharpening disks and centrally between the latter and having an elongated bearing at its upper end provided with a slot extending from end to end thereof, a rock-shaft journaled in said bearing and having a knife blade mounted lengthwise thereon and projecting radially therefrom, and means interposed between said first-mentioned shaft and said rock-shaft to rock the latter, said rock-shaft being lengthwise insertable into said elongated bearing and lengthwise removable therefrom and said knife blade being removable with said rock-shaft through the slot in said elongated bearing.

12. A machine for sharpening knives or the like, comprising a suitable support, a shaft transversely mounted on said support, two axially-aligned spaced-apart sharpening disks secured to said shaft, means to rotate said shaft, a standard mounted on said support in planes in rear of said sharpening disks and centrally between the latter and having an elongated bearing at its upper end provided with a slot, a rock-shaft journaled in said bearing and having a knife blade mounted lengthwise thereon and projecting radially therefrom, said shaft extending forwardly from its bearing into the space between said sharpening disks to position said knife blade for contact alternately with said sharpening disks, and means interposed between said first-mentioned shaft and said rock-shaft to rock the latter, said slot permitting removal lengthwise of said rock-shaft and its mounted knife blade from the rear of said bearing.

13. A machine for sharpening knives or knife blades, comprising a suitable support, a shaft transversely mounted on said support, two axially-spaced-apart sharpening disks secured to said shaft, means to rotate said shaft, a rock-shaft journaled above said support in rear of said sharpening disks and having its forward end extending between the latter, a knife or knife-blade holder carried by said rock-shaft and a knife or knife-blade secured thereto, means to cause said rock-shaft to rock and swing said knife or knife-blade alternately against opposing faces of said sharpening disks including an angular rod having two arms disposed at a right angle to each other, one of said arms being passed through said rock-shaft and the other being disposed substantially parallel therewith, and a retractile spring connected with said substantially parallel arm and with a point in fixed relation to said support, said last-mentioned means being actuated through the medium of said first-mentioned shaft.

ERWIN ROEDER.
